UNITED STATES PATENT OFFICE.

PAUL M. THAYER, OF PLYMOUTH, INDIANA.

AUTOMATIC STOKER FOR LOCOMOTIVES

1,109,802.

Specification of Letters Patent.

Patented Sept. 8, 1914.

Application filed March 6, 1913. Serial No. 752,313.

To all whom it may concern:

Be it known that I, PAUL M. THAYER, a citizen of the United States, residing at Plymouth, in the county of Marshall and State of Indiana, have invented certain new and useful Improvements in Automatic Stokers for Locomotives, of which the following is a specification.

This invention relates to automatic stokers, and is particularly adapted for use on locomotive engines.

One of the objects of the present invention is to provide a stoking means for furnaces, by which a positive and even feed of the fuel to the fire-box is obtained.

Another object of the invention is to provide an automatic stoker which has means whereby the feed of the fuel may be regulated.

20 A still further object of the invention is to provide an automatic stoker having means for imparting a step by step progressive feed of the fuel with means for directing the fuel upwardly into the fire box.

25 With these and other objects in view, the present invention consists in the combination and arrangement of parts hereinafter more fully described, illustrated in the accompanying drawings, and particularly

30 pointed out in the appended claims, it being understood that changes may be made in the form, proportions, size and minor details without departing from the scope or sacrificing any of the objects of the invention.

Upon referring to the drawings,

Figure 1 represents by dotted lines a side elevation of part of a locomotive, with the fire-box and the stoking devices in longitudinal section taken on a line $x-x$ of Fig. 2. Fig. 2, is a horizontal section of the fire-box taken on a line $y-y$ of Fig. 1. Fig.

35 3, is a longitudinal section of one of the stoking devices taken on the line 3-3 of Fig. 2. Fig. 4, is a longitudinal section taken on a line 4-4 of Fig. 2. Fig. 5, is a transverse sectional view of one of the coal chutes taken on a line 5-5 of Fig. 3. Fig. 6, is a similar view taken on the line

40 6-6 of Fig. 3. Fig. 7, is a similar view taken on the line 7-7 of Fig. 3. Fig. 8, is a horizontal fragmentary section taken on the line 8-8 of Fig. 6. Fig. 9 is a fragmentary detail view showing the positions of the reciprocating feed member at

45 its extreme fore and aft stroke. Fig. 10,

is a side elevation of the operating lever for controlling one of the deflector elements; and Fig. 11, is a similar view in end elevation.

In the drawings, the grate of the fire space box 1 comprises a plurality of spaced coal chutes 2 which diminish in height from their rear ends to their forward ends and which are substantially V-shaped in cross-section. Any 65 number of coal chutes may be employed, depending upon the size of the fire box, but I prefer to use three chutes, as shown in the drawings. The upper ends of the walls of the coal chutes 2 may be enlarged to provide beams 3 suitably supported at their ends and provided with spaced sockets 4 in which the trunnions 5^a of the grate castings 5 are seated, as shown in Figs. 2 and 6. The spaces between the chutes 2 are 70 spanned by the grate castings 5, whose trunnions, as above described, are seated in the sockets in the beam portions 3 of the chutes. It will be noted that by virtue of the decrease in height of the chutes from their 75 rear to the forward ends the beams 3 and the grate castings 5 are inclined forwardly. At the forward end of each grate section is provided a relatively large dump plate 6, 80 swingingly supported in any suitable manner as at 6^a, and which may be operated by any suitable means to remove clinkers and the like which work down toward the forward end of the grate by virtue of its inclination, as before described. The parts 85 immediately below each grate section are open and unobstructed so that the ashes may be dumped in the customary manner.

Each coal chute 2 is provided with a cover plate 7 which may be reticulated or provided with a plurality of openings 8, as shown in the drawings. From the forward ends of the openings 8 extend downwardly and rearwardly deflector plates 9, so that coal being shoved or moved through the chute toward the forward end thereof will be intercepted and deflected upwardly by the plates 9 through the openings in the cover plates 7 into the fire box. The interior surfaces of the side walls of the chutes 2 may be provided with deflector ribs or plates 10 having the same degree of angularity as the deflector plates 9, the deflector plates or ribs 10, coöperating with the plates 9 in the upward feed of the fuel. I have shown the ribs or plates 10 formed integral with the side walls of the chutes, but it is

obvious that these plates may be attached or secured in any suitable manner to the side walls.

In order to regulate the feed of the fuel, such as coal, so that the same may be fed more rapidly to one portion of the fire box than to another, one of the chutes as shown, or all of them if desired, may be provided with a swinging beam or arm 11 pivoted at 12 so as to swing preferably in a horizontal direction. The beam or arm 11 is provided with a plurality of deflector plates 13 having the same degree of angularity as the fixed deflector plates 9 and 10. The deflector plates 13 preferably project laterally from the side of the beam 11 adjacent the chute the feed of the coal in which it is desired to regulate by means of the deflector plates 13. These deflector plates 13 are adapted to enter or project through suitable slots 13^a formed in one of the side walls of the chute 2, the extent to which the deflector plates 13 project into the chute depending upon the degree of movement given the beam 11 on its pivot 12. The greater the distance of projection of the plates 13 into the chute the greater the obstruction to the passage of the coal through the chute at that point and a proportionate greater quantity of coal deflected upwardly. The beam 11 may be thus shifted so as to cause the fuel to be fed more rapidly at the coal supply or rear end of the chute and proportionately less further on and inversely, depending upon which end of the beam 11 is shifted toward the chute. As the coal is moved forwardly in the chute by any suitable means, such as those hereinafter described, the coal is deflected at some point in its passage through the chute and directed upwardly into the fire box by the fixed deflector plates 9 and 10 and by those deflector plates 13 that have been projected into the chute, the coal passing through the openings in the cover plates 7, which permit the distribution of the coal to extend over a large area. The coal that is not intercepted or deflected by the plates 9, 10, etc., is fed to the forward end of the chute and is directed upwardly into the fire box by means of the inclined plate or wall 14 and through the opening 15, as shown in Fig. 3.

The beam 11 may be swung or shifted on its pivot 12 by any suitable means. One manner of shifting this beam 11 I have shown in the drawings as comprising the bell crank levers 16 and 17 having suitable connections with each other and with one end of the beam, one arm of the bell crank lever 17 serving as the operating handle 18 and movable between two toothed segments 19 and 20. The handle 18 may be locked against accidental shifting by any suitable means, as by rods 21 and 22 spanning the space between the segments and disposed in

notches therein on each side of the handle so as to prevent movement of the latter in either direction. The operating handle 18 is preferably mounted without the fire-box, as shown in Fig. 2, so that ready access may be had to the handle for shifting the beam 11.

The lower ends of the coal chutes 2 may communicate with chambers 2^a in each of which a reciprocating carriage 23 may be mounted. The walls of the chambers 2^a may be formed of separate plates secured to the walls of the chutes 2, but I prefer to form the walls of the chambers 2^a by prolonging or extending downwardly the walls of the chutes, as shown in Figs. 5 and 6.

The walls of the chambers 2^a are provided with grooved guides formed in any suitable manner as by the shoulders 25^a and 25^b in which guideway the carriage 23 reciprocates. The carriage 23 is formed of side bars 24 and end members 26 and 27, the end members 26 and 27 having downwardly extending portions 28 which are secured to said side bars and are provided with apertures to serve as bearings for an operating or shift-rod 29 passing therethrough. Pivotedly mounted between said side-bars 24 are a plurality of push heads 30 which may be provided with downwardly extending portions 30^a preferably bifurcated to straddle the shift or operating rod 29. On each side of the bifurcated members 30^a are collars 31 which collars are fixed on the shift rod so that upon a shifting of the latter forwardly or rearwardly the members 30^a are moved forwardly or rearwardly as the case may be. On shifting the rod 29 forwardly the free forward ends of the push heads will be raised as shown in Figs. 3 and 9 and upon a reverse movement of the rod the push heads will be returned to their original or lowered position, as shown in Fig. 9.

The shift rod 29 may be provided with spaced collars 32 and 33 keyed or otherwise fixed to the rod and disposed on opposite sides of the end members 26 and 27 so that the shift rod 29 will have a limited movement relative to the carriage 23 to which the end members 26 and 27 are secured. Upon the first movement of the shift rod 29 forwardly the free ends of the push heads will be moved upwardly at which time the collars 33 will contact with the end members and shift the entire carriage 23, upon which said push heads are mounted, in a forward direction to a distance approximately the length of the push heads 30, as shown in full and dotted lines in Fig. 9. Of course, it is obvious that the carriage may be pushed forwardly any desired distance depending upon the location of the collars 32 and 33, etc. Upon the reverse movement of the shift rod 29 the ends of

the push heads 30 are lowered by virtue of the rod 29 having a movement independent of the carriage 23 before the carriage is moved rearwardly by the collars 32 engaging the end members of the carriage to shift the latter to its original position. The forward and rearward movement of the carriage in the manner stated causes the coal to be fed forwardly in a step by step movement 10 by the push heads 30 and with the coöperation of the deflector plates before described the coal or other fuel is fed upwardly into the chutes through the openings in the cover plates 7 into the fire box. The coal may be introduced into the rear end of the chute by any suitable means, as by hoppers 34 into which the coal is shoveled and from which it feeds by gravity into the chutes directly upon the reciprocating carriage 23. The shift rods 29 for actuating the carriage 23 and the push heads 30 may be operated by any suitable means, one means for operating the rods, as I have illustrated in the drawings, comprises the steam engine or motor 25 consisting of the cylinder 35* in which a piston 35 is operable with a valve controlling means of any suitable type (which I have not shown as it forms no material part of this invention). The piston 35 is connected by means of a connecting rod 36 with a lever 37 mounted on a rock shaft 38, upon which rock shaft may be mounted levers 39 connected with the ends of the shift rods 29 by means of short links 40, the latter allowing the shift rods 29 to be moved rectilinearly while the ends of the levers 39 describe a short arc in their fore and aft stroke.

The piston may have communication with 40 the steam chest of the locomotive or other boiler by means of a pipe 41 in which is located a valve 42 whereby the piston 35 and the feed mechanism operated thereby may be controlled for rapid or slow movement 45 depending upon the feed of the fuel that is desired.

A brief description of the operation of my invention is as follows: Fuel having been shoveled into the hoppers 34 is fed by 50 gravity onto the carriages 23. Upon opening the valve 42 in the pipe 41 the piston is reciprocated whereby the shift rods are moved back and forth alternately raising and lowering the push rods 30 and reciprocating the carriages 23, hereby a progressive feed is given the fuel in the chutes 2. As the coal is fed forwardly it is deflected upwardly by the deflectors 9, 10, etc., into the fire box, upon the grate castings 5.

60 It will be noted that the upper ends of the chutes, the upper surfaces of the cover plates and grate bars are substantially flush with each other. This may not be essential, but it provides a better grade for the fire 65 box and is conducive of a better feed of

the coal from the chutes upon the grate bars, as there are no ridges or the like to impede feeding or spreading of the coal in the fire box.

Various changes may be made in my invention without departing from the spirit thereof.

What I claim is:

1. An automatic stoker comprising in combination with the fire box, a plurality of 75 spaced coal chutes, grate castings spanning the spaces between the coal chutes, pushing means for pushing the coal forwardly of the coal chutes, perforated cover plates disposed over the upper ends of the coal chutes, 80 and deflecting means for directing the coal upwardly in the chutes through the openings in the cover plates and onto the grate castings.

2. An automatic stoker comprising in 85 combination with the fire box, a coal chute the upper end of the chute being open and communicating with the fire box, a reticulated cover plate disposed over the open end of the chute, deflector plates carried by the 90 cover plate, other deflector plates carried by the side walls of the chute, and means for feeding coal forwardly of the chute to be deflected upwardly into the fire box by the said deflector plates.

3. An automatic stoker comprising in combination with the fire box, a coal chute communicating with the fire box and provided with openings in one of its side walls, a swinging member mounted without the 100 chute and carrying a plurality of deflecting plates, means for swinging said member to selectively project a portion of the deflector plates carried thereby into the coal chute at different points in the length thereof, and 105 means for feeding fuel lengthwise of the chute to be deflected upwardly by the deflector plates carried by the swinging member.

4. A stoker comprising in combination 110 with a fire box, a plurality of coal chutes provided with converging longitudinal walls, said walls enlarged to form beams extending longitudinally of the fire box, grate bars supported by the longitudinal beams, 115 perforated cover plates supported at the upper ends of the chutes, said perforated cover plates lying substantially flush with the grate bars, feeding means in the chutes for imparting a progressive movement to the 120 coal in the chutes, deflecting means for directing the coal upwardly through the perforations in the cover plates out upon the grate bars, and a suitable operating means for the feeding means in the chutes.

5. In an automatic stoker, a coal chute having its upper end communicating with the fire box of a furnace, a perforated cover plate disposed over the upper end of the chute, depending deflector plates carried by 130

the cover plate, other deflecting means projecting from the side walls of the chute, and feeding means for imparting a progressive feed to the coal in the chute to be deflected 5 upwardly by the deflectors.

6. In an automatic stoker, a coal chute open at its upper end and communicating with the fire box of a furnace, one of the walls of the chute being provided with 10 spaced openings, a swinging arm mounted without the chute and provided with deflector plates for projection through said openings, additional deflecting means secured to the inner surfaces of the walls of the chute, 15 a perforated cover plate disposed in the upper end of the chute, depending deflector plates carried by the cover plate, and means for imparting a progressive feed for coal in the chute to be deflected upwardly by the 20 several deflecting means.

7. In a stoker, a coal chute, a reciprocating carriage disposed in the lower end of the chute, pusher heads swingingly mounted in the carriage and normally disposed in 25 inoperative position, a shifting rod supported by the carriage and having a limited relative movement thereto, means for operatively connecting each pusher head with the shifting rod, and means for imparting movement to the shifting rod for first swinging the pusher heads and subsequently moving the carriage.

8. In a stoker, a coal chute provided with converging side walls whose lower ends are 25 prolonged downwardly, suitable guides carried by the prolongations of the side walls,

a sliding carriage mounted in the guides, pusher heads swingingly supported by the carriage, a shifting rod operatively connected with the pusher heads, bearings on the 40 carriage for the shifting rod, spaced collars carried by the shifting rod on each side of said bearings to permit the shifting rod to have a limited rectilinear movement in the bearings and means for operating the shifting rod relative to the carriage to swing the pusher heads into operative position and for sliding the carriage upon the limit of movement of the shift rod being reached.

9. In a stoker, a coal chute provided with 50 converging side walls whose lower ends are prolonged downwardly, suitable guides carried by the prolongations of the side walls, a sliding carriage mounted in the guides, pusher heads swingingly supported by the 55 carriage, suitable bearings supported by the carriage, a shift rod slidably mounted in the bearings, stops on the shift rod on each side of the bearings for limiting the movement of the shift rod through the bearings in 60 either direction, connecting means between the push heads and the shift rod, and means for operating the shift rod to alternately swing the pusher heads and reciprocate the carriage.

In testimony whereof I affix my signature in presence of two witnesses.

PAUL M. THAYER.
